PARACHUTE PACK

Floyd Smith, Buffalo, N. Y., assignor to Irving Air
Chute Co. Inc., Buffalo, N. Y., a corporation

Original application March 31, 1937, Serial No.
134,109. Divided and this application March
14, 1938, Serial No. 195,884

3 Claims. (Cl. 244—148)

This invention relates to improvements in parachutes.

The present application is a division of my application Serial No. 134,109, filed March 31, 1937, now Patent 2,130,569.

The present application relates to improvements in parachute packs of the emergency type, and has particular reference to a semi-soft pack having a compact arrangement of details which will permit of an efficient packing and release of a parachute canopy with a high factor of safety.

Other objects and advantages of the invention will be apparent during the course of the following detailed description.

In the accompanying drawing, forming a part of this specification, and wherein similar reference characters designate corresponding parts throughout the several views,

Figure 1 shows an individual carrying the compact emergency pack.

Figure 2 is an inner view of the improved pack container opened and showing the relation of the shroud line assemblage therein.

Figure 3 is a view similar to Figure 2 but with the shroud lines completely assembled therein and showing the manner in which certain flaps protect the shroud lines against liability of entangling with coupling parts of the container.

Figure 4 is an external view of the container of the improved pack in an opened flattened condition.

Figure 5 is a perspective view of one of the coupling members of the pack.

Figure 6 is a cross sectional view taken through the coupling, showing its assemblage on the improved pack; the view being taken substantially on the line 6—6 of Figure 4.

Referring to the modified form of parachute pack shown in Figures 1 to 6 inclusive, the letter C' may generally designate the pack which may be applied to a single point quick release harness D', such as shown in Figure 1. This pack is also of the soft pack variety, except that it is only stiffened at the locations where the couplings are permanently connected to the pack. In this type of pack the couplings of the parachute canopy are permanently connected to the container so that the latter will not float away. However, the pack is otherwise of the soft variety and free of wire frame or other frame stiffening expedients.

The pack includes a flexible fabric container 130' having a base 131' (not wire reinforced along its boundaries). This pack also includes the usual side flaps 132' and flaps 133'. They have the usual eyelets, grommet pins, and conventional

rip cord apparatus now in standard use. The handle 140' for the rip cord 141' is releasably mounted in a pocket 142' upon a flap 133' of the container. The pack is of rather roll shape appearance and it is only stiffened along the longitudinal axis of the base 131' of the pack. The flaps 133' are provided with longitudinal flexible steel stays 133a. A narrow elongated wire frame 160 of rectangular shape is sewed by means of a flap in permanent position on the bottom 131' of the container. Button-hole like slots 161 are provided in alignment along the axis of the base 131', through which the coupling parts 163 are slipped. These coupling parts 163 have an external loop 164 which cooperates in a complementary coupling relation with the snap fasteners 34' of the harness, and internally of the pack they each have an elongated eye 165 through which the shroud lines are connected. These eyes 165 open transversely to the longitudinal axis of the base 131', and the shroud lines are divided into two parts and suitably connected, as shown at 170 in Figure 2 of the drawing, thru the eyes 165. The coupling parts 163 are themselves connected by cable means 173 to insure that if only one coupling part 163 is connected to only one of the snap fasteners of the harness, there will still be an equal distribution of load shock to all of the shroud lines of the parachute when the latter is opened during a drop. The coupling parts 163 maintain their transverse fixed immovable relation upon the rigidly framed portion of the base 131' by means of detachable rigid preferably metal retainer pieces 176 which, as shown in Figure 6, are slipped through close fitting openings 177 in the coupling parts 163, and maintain the eye portions 164 of said coupling parts in definitely spaced outstanding fixed relation upon the rigid portion of the container. If desired a handle 180 may be placed on the exterior of the base 131' to facilitate carrying of the pack, as shown in Figure 1.

Novel means is provided for packing the shroud lines in the pack and for guiding the shroud lines against disarrangement or entanglement, either with respect to one another or with respect to the parachute canopy. To that end internally of the container elongated guard flaps 185 are sewed or otherwise connected upon the base of the pack container at the outer ends of the coupling parts 163, as shown in Figures 2 and 3 of the drawing, which may fold over the eye portions 165 of the couplings 163, within the pack, in order to guard the shroud lines, and prevent entanglement thereof with respect to each other and

with respect to the coupling parts 163, as will be apparent from Figure 3 of the drawing. The base 131' at each end thereof, and laterally of the rigid frame portion thereof is provided with 5 a series of pockets or tabs 190, which permit the bight ends of the shroud lines to be tucked therein, with the shroud lines folded zig-zag, in order to permit their ready deployment. As shown in Figure 2 of the drawing the shroud 10 lines are bunched together at their ends adjacent the couplings 163 and are first folded into one of the pockets 190 and then extended back and forth zig-zag in substantial parallelism with the longitudinal axis of the base 131', and of 15 course in substantial parallelism with the line in which the couplings 163 lie. Thus it is to be noted that the shroud lines are folded on a flexible portion of the base 131' and in position so that when the base is distorted, due to close 20 compacting and packing of the folded parachute and shroud lines the lines will still lie parallel and in a straight line without bending, so that there will be no possibility of entanglement with respect to each other.

25 Various changes in the shape, size, and arrangement of parts may be made to the form of invention herein shown and described, without departing from the spirit of the invention or the scope of the claims.

30 I claim:

1. In an emergency parachute pack the combination of a container having a coupling secured thereto and provided with an interior portion and an exterior rigid outstanding portion,

a parachute having shroud lines, means connecting said shroud lines interiorly of the container to said coupling, a guard flap secured on the container for positioning directly over the interior portion of said coupling, and means 5 for folding and retaining the shroud lines in the container in guarded relation by said flap with respect to said coupling.

2. In an emergency parachute pack a container having a plurality of fixed coupling parts 10 thereon, a parachute having shroud lines, means connecting said shroud lines in bunched relation upon said couplings, a separate cable construction connecting said couplings together, and pocketing means on the container for housing 15 said shroud lines in lengths which run parallel with the cable that connects said coupling parts together.

3. In an emergency parachute pack a container having a flexible base portion and closure means therefor, a pair of affixed rigid couplings connected in aligning relation upon the container base and in spaced relation, means rigidly reinforcing only that portion of the base between and around said couplings, a parachute, 25 shroud lines for the parachute having bunched connection with said couplings, and pocketing means on the base of the container releasably housing the shroud lines in zig-zag bunched relation with the lengths thereof lying substantially parallel with a line extending between the coupling parts.

FLOYD SMITH.
